Application December 13, 1944, Serial No. 116,874

Term of patent 14 years

(CL. D92—2)

To all whom it may concern:

Be it known that I, Edna Royle Higley, a citizen of the United States, residing at Trenton, in the county of Mercer and State of New Jersey, have invented a new, original, and ornamental Design for a Blanket Wrap, of which the following is a specification, reference being had to the accompanying figures of the drawing, forming a part thereof.

Fig. 1 is a front view of a blanket wrap showing my new design;

Fig. 2 is a rear view of the blanket wrap shown in Fig. 1, and

Fig. 3 is a plan view thereof on a smaller scale. The essential features of my design reside in the combination on the blanket wrap disclosed, of the draped upper rear portion resulting from the insertion of the projecting end portion through the slot in association with the cape-like front, all as shown.

I claim:

The ornamental design for a blanket wrap, substantially as described and shown.

EDNA ROYLE HIGLEY.
